UNITED STATES PATENT OFFICE.

JOHN I. THROCKMORTON, OF CLARKSBURG, OHIO.

TRUSS.

1,272,577.

Specification of Letters Patent. Patented July 16, 1918.

Application filed March 17, 1915. Serial No. 14,905.

To all whom it may concern:

Be it known that I, JOHN I. THROCKMORTON, a citizen of the United States of America, residing at Clarksburg, in the county of 5 Ross and State of Ohio, have invented certain new and useful Improvements in Trusses, of which the following is a specification.

My invention relates to trusses and is directed to the provision of a device adapted 10 to relieve and serve as a support in cases of hernia. Its general principles are more or less similar to the principles of those trusses in common use to-day, being primarily distinguished from those with which I am familiar by the fact that the force which is ultimately applied to the rupture is comparatively local in nature and is not the result, necessarily of the entire structure of the 15 truss. As a consequence, the general structure of the truss may be made of such form that the pressure at the desired point will invariably exist, regardless of the position of, or the changes of position of, the body of 20 25 the wearer.

More specifically, my invention consists in the production of a truss which is supported upon the body by a flexible tape or strap structure yieldable with and conformable to 30 the twists and turns of the body. This strap structure supports a presser element adjustable as to pressure applied and so constructed that it will remain in applied position regardless of the movements of the body and 35 the consequent movements of the strap or tape structure.

Various other features of importance will appear as the following detailed description progresses. It will be noted that this detailed description is clarified by reference to 40 appended drawings, wherein similar characters of reference designate corresponding parts throughout the different views and wherein:

45 Figure 1 is a perspective view of my improved truss in its entirety.

Fig. 2 is a plan view of the presser element removed from the strap or tape structure.

50 Fig. 3 is a section taken on line 3—3 of Fig. 2.

Fig. 4 is a side-elevation of the presser element, illustrating the collapsing hinge structure to be described.

55 Fig. 5 is a detail in elevation of the outer end structure of the threaded member which

is adjustable to vary the pressure of the presser element, in a manner to be described.

Fig. 6 is a side elevation of sleeve structure which is utilized to facilitate regulation of the pressure of the presser element without apparent variation of external contour thereof.

Fig. 7 is a similar view taken at right angles to Fig. 6 and with the casing removed along line 7—7 of Fig. 6.

In the drawings, my truss is shown as comprising a waist strap 1 having its ends adjustably secured in buckles 2 on the base 3 of a presser element, it being noted that the buckles are carried entirely on the presser element thereby facilitating the replacement of the waist strap when it becomes worn or frayed.

In spaced relation to the base 3 is a plate element 4 which is fixed in parallelism therewith and against relative rotation by means of a hinge and other structure to be described. The plate 4 is provided at one side 80 with ears 5 and 6 upon which are mounted headed pins 7 and 8 for the retention of key-hole connectors 9 and 10 carried upon the opposite end of a thigh strap 11 which is adjustable by means of a buckle element 12.

From this described structure, it will be apparent that both the waist and thigh straps of my improved truss are adjustable as to length, while either may be readily detached at the presser element.

The base 3 is in the nature of a substantially oblong plate having its ends provided with transverse slots and pivoted prong elements which, together, form the buckles 2. Centrally disposed upon this plate is a 95 threaded bolt 13 having a shoulder 14 mounted thereon and a neck 15 which extends through the plate and is held therein by a collar pinned to such bolt, as at 16. By this construction, the bolt 13 is rotatable on the plate 3 and to facilitate such rotation, the bolt head is slotted as at 17. Mounted upon the plate 3 and inclosing the threaded bolt 13 is a cylindrical casing 18.

Connected to the plate 3 by a hinge 19 is 105 a second plate 4 which not only carries the headed pins 7 and 8 but which also carries a centrally located cylindrical casing 20 having an internal flange 21 at its outer end. The plate 4 is provided with an opening at 110 the inner end of this casing 20, which opening is of the same diameter as such casing.

Mounted upon the outer end of such casing 20 is a presser head 22 which is swiveled thereon through the medium of a plate 23 carried in a socket 24 and provided with a shoulder 25 for coaction with the internal flange 21 of the casing 20. Concentrically disposed on this plate 23 and therefore concentric with the casing 20 is a cylindrical sleeve 26 slotted as at 27 and carrying a slideable internally threaded sleeve 28 held therein and held against rotation by a laterally extending pin 29 working in the slot 27. The parts of the presser element are maintained against collapse upon each other by a coil spring 30 which is carried within the telescoping casings 18 and 20 and incloses the threaded bolt 13 and sleeve 26.

In operation, my truss is applied in a manner made apparent by Fig. 1 of the drawings and because of the swiveled head construction, this head 22 remains in applied position regardless of the changes of position of the straps by which the truss is applied. This is one of the important features of my invention. It will further be apparent that the straps are adjustable and yet may be readily released or connected. The pressure at the desired point comes from within the presser element, the plates being movable toward each other because of the hinge connection which coacts with the telescoping casings to maintain them in parallelism and which further prevents relative rotation of such plates. The threaded bolt co-operating with the internally threaded sleeve makes possible the ready adjustment of the spring tension without extension of the threaded bolt so as to cause protrusion or injury to the clothes of the wearer of the truss. It will be noted that the plate 23 is removably mounted in the socket 24 by screws.

Having thus described my invention, what I claim is:

1. In a truss, a presser element comprising a presser head capable of partial rotation and a supporting structure comprising hinged parallel plates.
2. In a truss, a presser head, a swivel head on said presser head, said presser head being capable of partial rotation, and a supporting structure comprising hinged parallel plates.
3. In a truss, a presser element, a supporting structure of collapsible box-like form and a threaded bolt and sleeve structure comprising an outer sleeve element, said outer sleeve element being slotted, an inner threaded sleeve element, a bolt to fit therein, and means on said inner sleeve element to prevent its rotating within said outer sleeve element.
4. In a truss, a presser element, a supporting structure comprising hinged parallel plates, a swivel element on said presser element comprising a threaded bolt and

sleeve structure constructed to permit the adjustment of said supporting structure and the independent rotation of either the presser element or said supporting structure.

5. In a truss, a presser element, and a supporting structure of a box-like formation, a swivel element on said presser element, comprising a sleeve element integral therewith, said sleeve element being slotted, an inner threaded sleeve, a bolt to fit therein, and means on said inner sleeve element to prevent its rotating within said first sleeve element, said swivel head being constructed to permit the rotation of either the presser element or said supporting structure.

6. In a truss, a supporting structure for a presser head comprising parallel plates hinged together, said plates being collapsible in parallelism without rotating.

7. In a truss, a supporting structure for a presser head comprising a base element, and an interconnecting element hingedly secured to said base element and collapsible in parallel relation thereto.

8. In a truss, a presser element capable of partial rotation and a supporting structure for said element comprising a base element and an interconnecting element hingedly secured to said base element, said base element and interconnecting element being yieldable in parallel relation.

9. In a truss, a presser element comprising a presser head, plates carrying said element and hingedly connected and in parallel relation to each other, said plates being constructed to collapse in parallelism.

10. In a truss, a presser head, and a resiliently telescoping structure comprising a resilient member, a base element and an interconnecting element collapsible in parallel relation thereto, said resilient member being disposed between said base element and presser head.

11. In a truss, a presser head and a supporting structure for said head comprising a base element and an interconnecting element, said base element and interconnecting element being collapsible in parallelism and adapted for the connection of a strap structure.

12. In a truss, a presser head and a supporting structure for said head comprising parallel plates hingedly secured and collapsible in parallelism, said plates being adapted to afford a combined rigid and spring action.

13. In a truss, a presser element comprising a presser head, a base element resiliently connected to said presser head, an interconnecting element rigidly connected to said presser head, said interconnecting element being hingedly secured to said base element, and means on said interconnecting element to provide upward pressure by said

presser head independently of any resilient member.

14. In a truss, a base element, a strap structure detachably connected to said base element for embracing the body, a presser head, said presser head and base element being connected by an interposed resilient means, an intermediate element connected to said presser head, and mechanism on said intermediate element for the connection of another strap, said mechanism be-

ing of such form and so mounted that said last strap will cause said presser head to exert a pressure independent of said resilient means.

15. In testimony whereof I, hereby affix my signature in presence of two witnesses.

JOHN I. THROCKMORTON.
